(57) **CLAIM**

The ornamental design for a tool handle, as shown.

DESCRIPTION

FIG. 1 is a perspective view of a tool handle showing my new design, with a broken line showing of a hammerhead and tool hanger;

FIG. 2 is a right side view in elevation of the tool handle of the present invention;

FIG. 3 is a top plan view of the tool handle of the present invention;

FIG. 4 is a bottom plan view of the tool handle of the present invention;

FIG. 5 is a front view in elevation of the tool handle of the present invention;

FIG. 6 is a left side view in elevation of the tool handle of the present invention; and,

FIG. 7 is a rear view in elevation of the tool handle of the present invention.

The broken line portion of the disclosure are for illustrative purposes only and form no part of the claimed design.
